SHOE POLISHING GUARD

Francis C. Shearing, Burlingame, Calif.

Application December 17, 1938, Serial No. 246,384

5 Claims. (Cl. 36—70)

My invention relates to improvements in a shoe polishing guard, and it consists of the combinations, constructions and arrangements hereinafter described and claimed.

5 An object of my invention is to provide a shoe polishing guard that is made of one piece of molded material such as rubber, and this material is designed to yieldingly engage with the leg to protect the hose. The device extends a slight distance down into the shoe and in this way the device is held in place. The guard has an integral rib that practically encircles the top of the device. This rib performs two functions in that it not only yieldingly holds the device in place, but it also prevents the polishing cloth from riding up over the device and onto the stocking.

10 A further object of my invention is to provide a device of the type described, that is extremely simple in construction and is durable and efficient for the purpose intended.

15 Other objects and advantages will appear in the following specification, and the novel features of the device will be particularly pointed out in the appended claims.

20 My invention is illustrated in the accompanying drawing forming a part of this application, in which

25 Figure 1 is a perspective view of a shoe, showing my device operatively applied thereto;

Figure 2 is a side elevation of the device;

30 Figure 3 is a longitudinal section through the device taken along the line 3—3 of Figure 4 and illustrates the position occupied by the device with respect to a foot and shoe; and

Figure 4 is a top plan view of the device.

35 In carrying out my invention, I provide a shoe polishing guard, preferably made from a molded material such as rubber. The guard is substantially oval in shape and has an inner wall 1, see Figure 4, designed to conform to the portion of the leg immediately adjacent to the shoe top. The guard is split and has two flaps 2 and 3 that slidably overlie each other. These flaps are long enough to permit the guard to be contracted or expanded to fit various sized legs.

40 In Figures 2 and 3, I show the upper outer side of the guard provided with an integral rib 4 that encircles the guard except for the small portions constituting the flaps 2 and 3. The rib 4 has its ends 4a terminating at the flaps to permit them to slidably overlie each other. Figure 2 shows how the outer flap 2 is cut away along its upper edge 5 to underlie the adjacent end of the rib 4. 45 The rib has a curved underside 4b that merges

5 into the body portion 6 of the guard. The body 6 has a depending flap 7 integral therewith and adapted to extend down inside a shoe 8 for a slight distance sufficient for the shoe to grip the flap and aid the rib in holding the device in place. A shoulder 9 is formed at the juncture between the body 6 and the flap 7 and this shoulder rests upon the upper edge 8a of the shoe. The flap 7 varies in length according to the portion of the leg or foot it covers. For example, the flap is 10 longer at the front of the device shown at 1a and this portion underlies the tongue and front of the shoe. The guard has recesses 10 on each side designed to accommodate the ankle bone of the wearer. I have found that a roughening of 15 the inner surface 11 of the body 6 will cause the body to frictionally engage with the hose and aid in holding it in position. The roughened inner surface may extend from the top of the guard to the bottom or it may extend over only a smaller 20 area of the device.

25 From the foregoing description of the various parts of the device, the operation thereof may be readily understood.

30 When applying the device to a leg 12, the device is opened along the flaps 2 and 3 to receive the leg and then the guard is allowed to return to its normal position. The rib 4 is resilient enough to cause the device to snugly grip the leg. The device is manually moved downwardly in order to cause the flap 7 to enter the shoe until the shoulder 9 abuts the upper edge 8a of the shoe. The flaps 2 and 3 overlap each other for a slight distance and this will assure protection 35 for the hose around the entire leg.

35 The shoe may now be polished in the ordinary manner and the device will receive any polish that is accidentally applied at a point higher than the top of the shoe. When a cloth is used for polishing the shoe, the rib 4 will act as a stop 40 to prevent the cloth from moving up over the top of the guard and onto the stocking when the cloth is being manipulated for polishing the top of the shoe. In this way, the guard performs a double function of clamping the device to a leg 45 and acting as a guide for the cloth. The rib is especially useful when the cloth is used for polishing the back of the shoe. The shape of the back of the shoe causes the cloth to slip upwardly and the rib prevents this. After the shoe is polished, the device may be readily removed without the necessity of unfastening any securing members. The device is preferably made of one piece of material which is molded in the manner shown.

50 While I have shown only the preferred form 55

of my invention, it should be understood that various changes or modifications may be made within the scope of the appended claims without departing from the spirit of the invention.

5. I claim:

1. A shoe polishing guard comprising a single molded piece of resilient material designed to encircle the leg at a point adjacent to the top of a shoe, said material being split in order to receive 10 the leg and having overlapping flaps positioned at the split, the upper edge of the guard having an integral rib that causes the guard to snugly engage with the leg, said rib also acting as a guide for a polishing cloth for preventing the 15 cloth from touching the stocking, a circumferential flap extending around the bottom of the guard and forming a shoulder at its joinder with the main body of the guard, said shoulder being adapted to rest on the upper edge of the shoe and 20 determine the depth at which the guard enters the shoe.

2. A shoe polishing guard comprising a single molded piece of resilient material designed to encircle the leg at a point adjacent to the top of a shoe, said material being split in order to receive 25 the leg and having overlapping flaps positioned at the split, the upper edge of the guard having an integral rib that causes the guard to snugly engage with the leg, said rib also acting as a guide 30 for a polishing cloth for preventing the cloth from touching the stocking, a circumferential flap extending around the bottom of the guard and forming a shoulder at its joinder with the

main body of the guard, said shoulder being adapted to rest on the upper edge of the shoe and determine the depth at which the guard enters the shoe, the interior surface of the guard being roughened for causing the guard to more effectively grip the leg. 5

3. A one piece shoe polishing guard designed to encircle the leg and having an integral rib for causing the guard to yieldingly and snugly engage with the leg, said rib projecting beyond the 10 outer surface of the guard and cooperating therewith to form a guide for a polishing cloth for preventing the cloth from contacting with the stocking. 15

4. A one piece shoe polishing guard made from 20 resilient material and designed to encircle the leg, an integral rib for aiding in causing the guard to grip the leg and also acting as a polishing cloth guide, said guard having a shoulder designed to contact with the upper edge of the shoe and to space the rib the desired distance thereabove, and a flap depending from the shoulder for 25 entering the shoe and aiding in holding the guard in place as well as protecting the stocking. 25

5. A shoe polishing guard comprising a sleeve-like member made of resilient material and designed to encircle the leg, the ends of the member overlapping each other, an integral rib disposed at the top of the member, a shoulder for engaging with the shoe top for spacing the rib thereabove, and a flap depending from the shoulder and designed to enter the shoe. 30
